FINISHING OF AVIATION NAPHTHAS

Boyd N. Hill, Baytown, Tex., assignor to Standard
Oil Development Company, a corporation of
Delaware

Application January 29, 1946, Serial No. 644,152

4 Claims. (Cl. 196—40)

1

This invention is a continuation-in-part of application Serial No. 542,318, filed June 27, 1944, now abandoned.

The present invention is directed to a method for processing the effluent from a hydrocarbon catalytic cracking operation particularly for the purpose of producing from said effluent the maximum quantity of high-grade aviation fuel.

The catalytic cracking of hydrocarbon distillates for the production of gasoline of high octane number is a well-known procedure in the art. In one conventional operation of this type, the hydrocarbon distillate in vapor form, admixed with steam and finely divided catalyst of the clay type, is passed through a cracking zone maintained at a temperature between about 900° and 1050° F. with the rate of flow of the reactants so adjusted that the finely divided catalyst is held in suspension and moves continually through the cracking zone in the direction of flow of the reactants. The feed to such an operation is usually a gas oil.

Various methods for processing the effluent from a catalytic cracking operation have been proposed. One conventional method is to isolate a fraction boiling between about 110° and 330° F., acid treat the fraction with about 93% to 98% sulfuric acid in an amount ranging from 5 to 25 pounds per barrel of distillate, and redistill the fraction for the removal of polymers produced by the acid treatment.

A second method for treating this effluent has been to subject it to catalytic hydrogenation directly following the cracking operation. This has the advantage that an increased yield is obtained and the need for an acid treatment is eliminated.

A third processing operation which has been practiced has been to subject the effluent to a second catalytic cracking operation or to thermal cracking. In this case the effluent from the second cracking operation again may be either acid treated and redistilled or catalytically hydrogenated.

In discussing these conventional treatments,

2

as well as the treatments according to the present invention, reference will be made to two different types of aviation fuel anti-knock rating. One of these is designated as AFD 1-C and the other as AFD 3-C. These ratings have definite meanings to those engaged in the production of aviation fuel and for the purpose of this description need not be elaborated on further.

Hydrogenation converts olefins to paraffins. Since low boiling paraffins, especially isoparaffins, have premium AFD 1-C characteristics and at the same time have relatively satisfactory AFD 3-C characteristics, hydrogenation tends to improve both of these characteristics to the extent that it converts low boiling olefins into isoparaffins. This is offset to some extent, however, by the fact that high boiling paraffins have poor AFD 1-C and AFD 3-C characteristics so that it is undesirable to convert high boiling olefins into paraffins. The hydrogenation treatment does have the advantage that it results in yields of about 100%.

Acid treatment, followed by redistillation, removes olefins which are of poor AFD 1-C rating and also of poor AFD 3-C rating when used to operate a motor on a rich mixture. Hence, acid treatment has the effect of increasing both the AFD 1-C and the AFD 3-C ratings. This procedure, however, has the disadvantages of not removing certain undesirable paraffinic materials in the high boiling range fraction and of being accompanied by treating losses.

Thermal re-cracking operations, on the other hand, tend to convert both high boiling olefins and high boiling paraffins partly to lower and higher boiling olefins and partly to aromatics. This operation has the effect of increasing both AFD 1-C and AFD 3-C ratings as a result of removing the high boiling paraffins having lower AFD 1-C and AFD 3-C ratings than the olefins produced in the operation. A loss of material, as compared with hydrogenation, also results from this operation. By combining re-cracking, acid treating and redistillation operations, further increases in both AFD 1-C and AFD 3-C

ratings over those obtainable by recracking or acid treating operations, taken alone, may be achieved.

According to the present invention, the effluent from a catalytic cracking operation is processed in such a way as to impart to it the maximum AFD 1-C and AFD 3-C ratings for a given yield. This is accomplished according to the present invention by dividing the effluent into fractions. There should be at least two fractions, one boiling between about 110° F. and 210° F. and the other boiling between about 210° F. and 330° F. If desired, a third fraction boiling between about 210° F. and 270° F. is segregated in which case the second fraction will boil between about 270° F. and 330° F.

In operating according to the present invention, the lowest boiling fraction is always hydrogenated. The highest boiling fraction is always subjected to a processing which includes a recracking treatment and a treatment with concentrated sulfuric acid of the conventional type, referred to above, followed by redistillation.

The intermediate fraction may be treated similarly to either of the other two fractions. In certain cases, it may be found preferable to hydrogenate the intermediate fraction in which case it is combined with the lowest boiling fraction during the hydrogenation of the latter. Alternatively, it may be desirable merely to acid treat and redistill the intermediate fraction, although the heaviest fraction is recracked, acid-treated and redistilled. Finally, the intermediate fraction may be combined with the heaviest fraction and subjected to the same treatment as the latter.

The nature of the present invention may be better understood from the following detailed description of the accompanying drawing in which the single figure is a front elevation in diagrammatic form of an apparatus in which the various types of treatment employed in the present invention may be conducted.

Referring to the drawing in detail, numeral 1 designates a catalytic cracking unit. A conventional gas oil is fed through line 2. The effluent from the catalytic cracking unit is discharged into a fractionator 3 from which fixed gases are withdrawn at the top through line 4. Bottoms are withdrawn from the fractionator 3 through line 5. One or more recycle cuts are withdrawn as side streams through outlet 6 and naphtha is withdrawn as a side stream through line 7. This naphtha cut will usually have a boiling range from about 110° F. to about 330° F. It is fed to a second fractionator 8 which is so operated as to provide three side streams, the upper boiling between about 110° F. and 210° F. being carried off through line 9, the middle boiling between about 210° F. and 270° F. being carried off through line 10 and the bottom boiling between about 270° F. and 330° F. being carried off through line 11.

Line 9 feeds the light fraction to a catalytic hydrogenation unit 12. The details of this hydrogenation step are well known in the art and do not constitute a part of the present invention. In general, this hydrogenation is of the non-destructive type carried out at a temperature ranging between 400° F. to 700° F. and under a pressure of between 100 to 750 pounds per square inch while utilizing an active hydrogenation catalyst as an example of which may be mentioned a catalyst composed of about 2 parts of nickel sulfide and 1 part of tungsten sulfide,

usually employed in pellet form. The hydrogenation unit, illustrated by a single rectangle in the drawing, includes the usual auxiliary equipment, such as condensers and fractionators, from which is recovered a hydrogenated product which is conducted by line 13 to an accumulator 14, out of which it is fed out of line 15 into a blending line 16.

The middle stream, as shown in the drawing, 10 is conducted by line 10 provided with a valve 11 to an acid treating unit 18 from which the acid treated product is discharged through line 19 into a still 20 from which the refined product is recovered overhead through line 21 and conducted 15 to an accumulator 22 which is also connected to blending line 16 by line 23. The polymers formed during the acid treatment are removed as bottoms from still 20 through line 24.

The bottom fraction is fed by line 11 to a thermal cracking unit 25. This unit is operated at a temperature within the range of about 900 to 1100° F. and under a pressure of between about 700 to 900 pounds per square inch. Again, with respect to this unit, it is to be understood that the rectangle 25 includes all of the auxiliary equipment, such as separators and fractionators, required to isolate the desired product of a boiling range substantially the same as the feed to the unit 25, which is conducted from the unit 25 through line 26 to an acid treating unit 27 from which the refined hydrocarbons are fed through line 28 to line 19 and into still 20.

It is to be understood with respect to both of the acid treating units, represented in the drawing by rectangles 18 and 27, that these units include all auxiliary treatments associated with conventional acid treatment such as sludge separation, and water washing and alkali neutralization of the oil.

40 Line 10 is connected to line 9 by line 29 provided with a valve 30. It is also connected to line 11 by line 31 provided with a valve 32. If the middle fraction is to be hydrogenated, valves 17 and 32 are closed and valve 30 is opened. If 45 it is to be simply acid treated, valves 30 and 32 are closed and valve 17 is opened.

In order that a finished product may be produced, there is connected to blending line 16 a supply of high octane blending agents 33. These 50 blending agents will ordinarily be isoparaffins of suitable boiling range either obtained by distillation or by alkylation of olefins, alkylated aromatics, hydrogenated polymers, selected aromatics and the like.

55 Reference is made to the following table in which are compiled data showing the effect of different processing steps on the AFD 1-C and AFD 3-C ratings of the three fractions of catalytic cracking effluent discussed above. In this 60 table the fractions identified are fractions of a cracked effluent obtained by catalytically cracking mixed paraffinic gas oils with approximately 60% conversion per pass at a reactor temperature of 945° F., a catalyst oil ratio of 4.3 and 65 weight of oil per hour per weight of catalyst of 4.9 (W./hr./W.). The hydrogenation was conducted at a temperature of about 500° F. with a pressure of about 165 pounds per square inch and in the presence of a catalyst composed of nickel sulfide and tungsten sulfide. The acid employed for the acid treatment was 98% sulfuric acid. The thermal after-treatment (recracking) was conducted at a temperature of about 930° F. under a pressure of about 750 pounds per square inch 70 with a feed rate of 5100 barrels per stream day.

The octane and rich mixture data given are based on correction of each fraction to 7 pounds Reid vapor pressure with isopentane and addition of 4 cc. tetraethyl lead per gallon.

ing that if desired this fraction can be included with the first fraction in the hydrogenation.

The heaviest fraction shows very little improvement in the AFD 1-C and AFD 3-C ratings

TABLE

Comparison of catalytically cracked naphthas finished by (1) hydrogenation, (2) treatment with 10 pounds of acid per barrel, and (3) thermal re-cracking plus 10 pounds of acid per barrel

Referring to this table, it will be seen that hydrogenation of the light fraction results in an increase of over 9 in the AFD 1-C rating with a 100% yield. When this light fraction is merely acid treated, the AFD 1-C rating is increased only about 2.5 and the AFD 3-C rating is also increased about 8.5. It is to be noted, however, that there is a considerable loss of yield in the order of 20%. It may be observed here that the fraction used for the acid treatment and combination thermal and acid treatment was from a different catalytic cracking effluent than that used for the hydrogenation. The data given, however, are for the purposes of comparison and are competent for indicating the order of improvement.

When the light fraction is given a thermal re-cracking treatment followed by acid treatment, the AFD 1-C rating is increased about 4 points and the AFD 3-C rating is increased about 15 points, but the yield is decreased more than 50%.

Referring to the middle fraction, it will be observed that hydrogenation increases the AFD 1-C rating about 6.5 points, but decreases the AFD 3-C rating by 2 points with a 100% yield. Acid treatment of this middle fraction results in an increase in AFD 1-C rating of 5.9 and an increase in AFD 3-C rating of 7 with a loss of yield amounting to about 9%. When this fraction is given a thermal re-cracking treatment followed by acid treatment the AFD 1-C rating is increased 11.6 points and the AFD 3-C rating is increased 28 points with a loss of yield of about 37%. Here it will be seen that as to this fraction there is a much greater increase in AFD 1-C and AFD 3-C ratings for a given loss of yield than in the case of the first fraction where thermal treatment followed by acid treatment is employed. It is to be noted, however, that with this fraction improvement of the same order of magnitude of the AFD 1-C rating is obtained by hydrogenation as with the first fraction indicat-

35 by hydrogenation, there being an increase of about 2 points in the former and a decrease of 1 point in the latter.

Acid treating, however, of this fraction resulted in an increase of 4.4 points in the AFD 1-C rating and in 9 points in the AFD 3-C rating with a very minor loss in yield. This fraction was subjected to thermal treatment followed by acid treatment and showed an increase in the AFD 1-C rating of 8 points and in the AFD 3-C rating of 32 points with a loss of yield of about 20%. Since it is this combination treatment which also gave considerable improvement in the AFD 3-C rating of the middle fraction, the latter will be processed with the third fraction or with the first fraction depending upon whether it is desirable to build up the AFD 1-C rating or the AFD 3-C rating.

From the data shown, it will be clear that the maximum improvement in AFD 1-C rating and AFD 3-C rating for a given yield can be realized by hydrogenating the fraction boiling between about 110° F. and 210° F. and subjecting the fraction boiling between about 210° F. and 330° F. to re-cracking followed by acid treatment and re-distillation. This is the preferred mode of operation according to the present invention.

It is to be understood that the references to cuts having certain boiling ranges herein are not intended to establish fixed limits on these boiling ranges, but are intended only to indicate the character of the differences in boiling ranges of the separate fractions which are subjected to different treatments. It is quite clear, from the fact that the middle fraction responds satisfactorily either to the treatment preferred for the first fraction or the treatment preferred for the third fraction, that the end boiling point of the first fraction can be any place between 210° F. and 270° F. or slightly higher. By the same token the initial boiling point of the third fraction can

be anything between 270° F. and 210° F., or slightly lower.

The nature and objects of the present invention having been fully described, what I wish to claim as new and useful and to secure by Letters Patent is:

1. A method for processing the effluent from a hydrocarbon catalytic cracking operation which comprises dividing said effluent into at least two fractions, one of said fractions comprising at least a major portion of constituents boiling between about 110° F. and 210° F. to the exclusion of constituents boiling above about 270° F. and another of said fractions comprising at least a major portion of constituents boiling between about 270° F. and 330° F. to the exclusion of constituents boiling below about 210° F. and comprising paraffins and aromatics, subjecting the first named fraction to catalytic hydrogenation, subjecting the second named fraction to a refining procedure including thermal cracking to convert paraffins to olefins followed by treatment with concentrated sulfuric acid sufficient to remove said olefins without substantially reducing the aromatic content thereof, and recombining said fractions after their respective treatments.

2. A method for processing the effluent from a hydrocarbon catalytic cracking operation which comprises separating from said effluent two fractions, the first having a boiling range between about 110° F. and 270° F., and the second having a boiling range between about 270° F. and 330° F. and comprising paraffins and aromatics, subjecting the first fraction to catalytic hydrogenation, subjecting the second named fraction to a refining procedure including thermal cracking to convert paraffins to olefins followed by treatment with concentrated sulfuric acid sufficient to remove said olefins without substantially reducing the aromatic content thereof, and recombining said fractions after their respective treatments.

3. A method for processing the effluent from a hydrocarbon catalytic cracking operation which comprises separating from said effluent two frac-

tions, the first boiling between about 110° F. and 210° F., and the second boiling between about 210° F. and 330° F. and comprising paraffins and aromatics, subjecting the first fraction to catalytic hydrogenation, subjecting the second named fraction to a refining procedure including thermal cracking to convert paraffins to olefins followed by treatment with concentrated sulfuric acid sufficient to remove said olefins without substantially reducing the aromatic content thereof, and recombining said fractions after their respective treatments.

4. A method for processing the effluent from a hydrocarbon catalytic cracking operation which comprises separating three separate fractions from said effluent, the first having a boiling range between about 110° F. and 210° F., the second having a boiling range between about 210° F. and 270° F., and the third having a boiling range between about 270° F. and 330° F. and comprising paraffins and aromatics, subjecting the first named fraction to catalytic hydrogenation, subjecting the second named fraction to treatment with concentrated sulfuric acid, subjecting the third named fraction to thermal cracking to convert paraffins to olefins followed by treatment with concentrated sulfuric acid sufficient to remove said olefins without substantially reducing the aromatic content thereof, and recombining the several fractions after their respective treatments.
